W. L. HAYNES

CENTRIFUGAL CASTING APPARATUS

Filed Sept. 19, 1922

Inventor:
William L. Haynes
by Francis J. Charles
his Attorney.

UNITED STATES PATENT OFFICE.

WILLIAM L. HAYNES, OF BURLINGTON, NEW JERSEY, ASSIGNOR TO UNITED STATES CAST IRON PIPE & FOUNDRY COMPANY, A CORPORATION OF NEW JERSEY.

CENTRIFUGAL CASTING APPARATUS.

Application filed September 19, 1922. Serial No. 589,062.

To all whom it may concern:

Be it known that I, WILLIAM L. HAYNES, a citizen of the United States of America, and resident of Burlington, county of Burlington, State of New Jersey, have invented certain new and useful Improvements in Centrifugal Casting Apparatus, of which the following is a true and exact description, reference being had to the accompanying drawings, which form a part thereof.

My invention relates to centrifugal casting apparatus, in which the melted metal is introduced into the rotating mold through a trough and in which the mold and trough are relatively retractable so that the trough can be fully entered in the mold or entirely retracted therefrom. More particularly, though not exclusively, my invention is intended for use in the de Lavaud type of apparatus in which the trough is used as a runner delivering melted metal from its open end while the mold is being retracted.

In centrifugal molding apparatus as heretofore constructed time is lost owing to the necessity of cleaning out the trough or runner between successive molding operations and it is the object of my invention to provide an improved apparatus which will provide for the cleaning of a used trough or runner while the machine is in use and under more convenient conditions than has heretofore been the case.

Generally speaking, my invention consists in providing in connection with a centrifugal mold, longitudinally movable with relation to its feed trough, a transversely movable trough supporting carriage on which are secured two parallel feed troughs spaced apart so that one can enter the mold and the other extend outside the mold and its supports.

My invention will be best understood as described in connection with the drawings in which—

Figure 1 is a plan view of my improved molding apparatus, and

Figure 2 a sectional elevation on line 2—2 of Fig. 1.

A indicates the framing supporting the molding apparatus and A' tracks or guide-ways on which the casing enclosing and supporting the rotatable mold moves to and fro. B is a cylinder for moving the casing and mold, B' being a piston in said cylin-

der; B² the piston rod and B³ the head by which the rod is attached to the casing C which forms a water jacket for the mold D with water tight joints at C' and C²; a turbine chamber at C⁴ enclosed between head C² and a wall C³. C⁵, C⁶, are supporting rolls for the mold D which has attached to one end the turbine ring D' from which blades extend into chamber C⁴. The above features are those of the well known de Lavaud apparatus, as shown, for instance, in Patent No. 1,329,295 of January 27, 1920.

E, E, are supporting guides secured to the framing and running at right angles to the axis of the mold and F is a trough supporting carriage transversely movable on said guides and supporting two troughs or runners, one indicated at G G' and the other at g g'. G² and g² indicate the open ends of the runner trough through which the metal enters the mold. The troughs are parallel to each other and spaced as shown so that one can enter the mold and the other extend alongside the casing.

H, H, are supports for the supply ladle I which is pivotally supported on the studs H' H' through its arms I', I' to one of which is secured a pin I² to which is connected the piston rod J' of a piston moving in cylinder J.

K is a cylinder for moving the carriage F through its piston rod K'.

The dotted line P, Fig. 1, indicates a position of the left hand end of the mold and casing to which they must move to clear the ends of the runner trough.

In operation and with the illustrated apparatus, a trough or runner as G, is shifted with its carriage so that it registers with the mold and with the ladle I. The mold is moved over the trough to the position shown and set in rotation and molten metal poured into the trough from the ladle and as the metal enters the mold through the open end G² of the trough the mold is moved towards the right until it is fully charged with the casting and, after perhaps a rest, the mold is still further retracted until the end of the trough is entirely cleared. The casting is removed from the mold but before pouring again the carriage F is moved until the trough g, g' registers with the mold and ladle and while a new casting

is being poured the trough G, G', can be conveniently cleaned preparatory to re-use. In this way the troughs are prepared for re-use without delaying the casting operation.

Having now described my invention, what I claim as new and desire to secure by Letters Patent, is:

1. In a centrifugal casting machine, a rotatable mold in combination with a trough supporting carriage movable in a plane transverse to the axis of the mold, two parallel troughs secured to said carriage at a distance apart which will permit one trough to enter the mold and the other to clear the mold supporting mechanism, and means for giving a relative longitudinal movement to the mold with reference to the troughs whereby the trough in registry with
- 10
- 15

the mold can be fully inserted in or fully 20 withdrawn from the mold.

2. In a centrifugal casting machine a longitudinally movable rotatable mold in combination with a transversely movable carriage and two parallel troughs secured to 25 said carriage spaced apart so that one trough can enter the mold and the other clear the mold supports.

3. In a centrifugal casting machine a longitudinally movable rotatable mold in combination with a transversely movable carriage, two parallel troughs secured to said carriage spaced apart so that one trough can enter the mold and the other clear the mold supports and a ladle for melted metal 30 located to register with the trough in registry with the mold.

WILLIAM L. HAYNES.
